CLAIM

The ornamental design for a charging base for handle, as shown and described.

DESCRIPTION

FIG. 1 is a perspective view of a charging base for handle according to an embodiment of my design;
 FIG. 2 is another perspective view thereof;
 FIG. 3 is a front elevational view thereof;
 FIG. 4 is a rear elevational view thereof;
 FIG. 5 is a left side elevational view thereof;
 FIG. 6 is a right side elevational view thereof;
 FIG. 7 is a top plan view thereof; and,
 FIG. 8 is a bottom plan view thereof.

The broken lines in the drawings depict portions of the charging base for handle that form no part of the claimed design.

The oblique shade lines in the drawings show transparency.
